WILLIAM HOOPES, OF PITTSBURGH, PENNSYLVANIA, ASSIGNOR TO ALUMINUM COMPANY OF AMERICA, OF PITTSBURGH, PENNSYLVANIA, A CORPORATION OF PENNSYLVANIA.

ELECTRICAL RESISTOR.

1,398,373.

Specification of Letters Patent. Patented Oct. 11, 1921.

Application filed October 2, 1919. Serial No. 327,954.

To all whom it may concern:

Be it known that I, WILLIAM HOOPES, a citizen of the United States of America, and a resident of Pittsburgh, in the county of Allegheny and State of Pennsylvania, have invented an Improvement in Electrical Resistors, of which the following description, in connection with the accompanying drawings, is a specification, like characters on the drawings representing like parts.

This invention relates to electrical resistors.

The invention and its aims and objects will be best understood from the following description, taken in connection with the accompanying drawings, of a resistor construction embodying one form of said invention selected for purposes of illustration, it being understood that the invention in its true scope is definitely set forth by the appended claims.

In the drawings:

Figure 1 is an elevation of one illustrative form of resistor or resistor unit embodying certain features of my invention;

Fig. 2 shows a vertical longitudinal section of the illustrative form of resistor shown in Fig. 1 with an illustrative form of means according to my invention for maintaining electrical contact of the parts where said contact is liable to become impaired in use; and

Fig. 3 is a detail of the lower portion of the tube 8 and pipe 12, and the casting 10.

In accordance with my invention the resistor may comprise any desired number of resistor elements. Referring to the drawings, the resistor therein shown comprises a series of eight such resistor elements 2, placed in line and each in electrical contact with the one next to it. A member of electrically conductive material, herein exemplified by a carbon block 4, will preferably be placed in contact with the resistor element at one end of the series, and another such carbon block 6 in contact with the resistor element at the other end of the series, these blocks 4 and 6 thus constituting what may conveniently be termed the contact electrodes.

An electrical conductor 8 of any suitable material, preferably of copper, and in the illustrative embodiment of the invention herein shown, extending longitudinally of the series of resistor elements 2, has one end adapted to be connected to one terminal of the electric circuit by which the resistor is

to be supplied with current, while the other end of said conductor is electrically connected by any suitable means to the resistor element at one end of the series while being maintained out of contact with the others. By connecting the resistor element at the other end of the series of said elements with the other terminal of the electric circuit serving to supply current to the resistor, current may be passed through the latter.

In the illustrative embodiment of the invention herein shown, the conductor 8 extends substantially axially through the series of resistor elements 2 and through the carbon blocks 4 and 6. I may use any suitable means for establishing electrical contact between the conductor 8 and the resistor element at one end of the resistor, said means herein comprising a metal casting, 10, preferably of copper to which one end of the conductor is secured in any suitable manner and which abuts against the end face of the carbon block 4.

In accordance with my invention I preferably provide cooling means for the conductor 8 to prevent overheating of the latter. To that end, in the illustrative form of the invention herein shown, said conductor will preferably consist of a copper tube. A pipe 12 is herein provided extending substantially axially through the tube 8 and having its inner end opening into the casting 10, provided with an interior chamber 14. The tube 8 surrounding the pipe 12 is preferably screw threaded exteriorly at its inner end which latter is screwed into a screw threaded opening extending through the wall of said casting 10. The pipe 12 is of smaller exterior cross section than the interior cross section of the tube 8, and at its free end projects from the free end of the tube 8, to which it is sealed at 16 in any suitable manner to form a fluid tight junction. The free end of the tube 8 terminates in an L 18 into which is screwed an overflow pipe 20. The free end of the pipe 12 is connected by any appropriate connection to any suitable source of supply, not shown, of water or other fluid cooling agent preferably under pressure. I preferably use water, the supply of water to the pipe 12 being controlled by any suitable means, such as a valve 22. Cold water may thus be admitted into the pipe 12 through which it passes downward into the hollow copper casting 10 and thence upward through the annular space between the

pipe 12 and tube 8, whence it is discharged through the overflow pipe 20. It is thus possible continually to maintain the conductor 8 and the other above described metal parts at temperatures below the boiling point of water, irrespective of how much heat they may be subjected to on the outside. Efficient cooling means is thus provided for the conductor 8 and other metal parts described, whereby overheating thereof is prevented.

In order to intercept as much heat as possible, I may, however, provide additional means to that effect. In the illustrative embodiment of the invention herein shown, said heat intercepting or insulating means may conveniently comprise the following instrumentalities.

Upon the lower end of the tube 8 is fitted a block 24 of any suitable heat-insulating and electrically non-conductive material, such as aluminum nitrid for example. This block rests upon the upper surface of the casting 10 and will preferably be of an exterior cross-section somewhat less than the cross-section of the axial opening provided in the carbon block 4. Upon said block 24 rest end to end a series of sleeves 26, preferably of graphite, said sleeves surrounding the tube 8 and having an interior diameter greater than the exterior diameter of said tube 8 and an exterior diameter preferably smaller than the interior diameter of the resistor elements 2. The sleeves 26 are preferably separated from each other by separating blocks 28 fitted upon the tube 8 and made of any suitable electrical and heat-insulating material. These blocks 28 serve to keep the graphite sleeves 26 properly spaced from the tube 8 and electrically insulated from each other for a purpose hereinafter more fully described. The annular space between the sleeves 26 and the tube 8 will preferably be filled in with any suitable heat-insulating material 30 of high heat-resisting properties. Powdered alumina, powdered magnesia or any other well-known electrically non-conductive powdered material may be used for this purpose. The annular space between the interior wall of the carbon block 4 and the outer wall of the block 24 may also be filled in with this or a similar heat-insulating material.

It will be apparent to those skilled in the art that the heat which would otherwise pass inward from the resistor elements 2 to the water-cooled conductor 8 will be mostly intercepted by the layer 30 of high heat resisting material, whereby the amount of heat passing into the cooling water will be reduced to a minimum.

The proper composition of the blocks 28 is dependent upon the purpose for which the resistor unit is to be used and the temperature to which it is to be subjected. For

a temperature of 1800° C. or over I preferably make these blocks of aluminum nitrid of high purity, as this compound possesses a higher resistance to high temperatures than any other commercially available material known to me, but any other suitable material having the necessary high coefficient of heat resistance may be used. For lower temperatures other less expensive refractory materials may be employed.

Over the water-cooled casting 10 there will preferably be placed a cap or covering of heat-insulating material 32 to prevent influx of heat into this casting. I preferably use for this purpose a cap of carbon secured to said casting in any suitable manner.

The resistor or resistor unit shown in Fig. 1 is complete and ready for use in connection with any suitable form of apparatus, which latter will of course vary according to the purpose for which the resistor is to be used. In use the current passes inward through the tube 8 into the water-cooled casting 10, thence into the carbon block 4 and thence into the end resistor element 2 in contact with said block 4 and so on through the entire series of resistor elements into the carbon block 6 at the other end of said series.

On account of the relatively high conductivity of the copper conductor 8 and copper casting 10, and the fact that these are cooled, it is possible to lead current through said conductor in sufficiently large quantities to heat the resistor to high temperatures.

It will be apparent to those skilled in the art that my invention is not limited to resistors of any particular form or type, but is applicable to resistors in general. The invention is very useful in practicing processes involving chemical reactions where the heat necessary to the reaction is supplied by electrical energy, on the resistance principle of heating, the charge itself constituting a resistor within which the heat necessary for the reaction is thus developed. Where my invention is applied to this use the resistor elements 2 will consist of self-sustaining blocks containing the ingredients that are to take part in the reaction. Thus, in the application of the invention to the nitrification of charges consisting of aluminous material the resistor elements 2 constitute the charge and will comprise a mixture of any suitable aluminous material, a suitable carbonaceous material, such as coke or coal, for example, to act as reducing agent, and a suitable binder. I preferably use for this purpose a mixture comprising powdered bauxite, coke and tar in the proportions of about 50 pounds of powdered bauxite, about 25 pounds of coke and about 25 pounds of tar. These ingredients having been thoroughly mixed, the mixture is formed into

- the self-sustaining blocks of a porosity to be permeable to gases. This may be done in any suitable manner and by any suitable means, but to that end I conveniently 5 press and bake the mixture in suitable molds of the form desired. Blocks of any suitable shape or size may thus be obtained, but I prefer to use either cubical or cylindrical blocks. Herein the blocks are shown as 10 cylindrical, about 12 inches high, 16 inches in diameter and provided with a six-inch hole cored in the center through which extends the electrical conductor 8 with its associated parts above described.
- 15 For a full description of blocks that may be used for this purpose and of the process of making same, reference is hereby made to my pending application Serial No. 324,767 filed September 19, 1918.
- 20 In carrying out the reaction the resistor will be placed in the reaction chamber of a furnace or other suitable apparatus and a nitrogen containing gas will be conducted into the reaction chamber in order that it 25 may permeate the blocks constituting the charge while an electric current is passed through the charge as already described. Nitrification of the alumina in the blocks will thus be effected, and when the nitrification 30 is completed the blocks may be removed from the resistor, ground up and the aluminum nitrid therein formed by the reaction extracted therefrom by any well known process.
- 35 Where the resistor is thus used for the purpose of nitrifying aluminous charges or for carrying out any other process involving reactions between solid and gaseous bodies, it is preferable that the nitrogen 40 gas or other gas used, according to the reaction contemplated, shall have access to the interior as well as to the exterior of the charge blocks 2. This I may provide for in any suitable manner, the carbon blocks 4 and 45 6 being herein conveniently provided with gas passages 34, for that purpose. The gas will thus have free access to the annular space 34 and to the inner walls of the blocks 2, as well as to the outer walls of the latter.
- 50 It will be apparent that instead of using a plurality of cored blocks, as described, a single cored block of the desired length may be used.
- Where the resistor is intended simply to 55 generate heat, for example as a heating element in a furnace or other apparatus, the resistor elements 2 may consist of laminated carbon plates, the necessary resistance being obtained by the contact resistances of said plates. Or the resistor elements 2 may 60 consist of any other suitable material, depending upon the purpose for which the resistor is to be used and the temperature to be attained. It is possible to attain very 65 high temperatures and very high resistances
- by making the resistor elements of refractory materials which are non-conducting at ordinary temperatures but which become conductive after being preheated. Zirconia is an example of a suitable material for making such resistors. For lower temperatures 70 resistor elements of alumina, magnesia, or other refractory material, may be used and thus much higher temperatures can be obtained than are obtainable by means of metallic resistance; furthermore leakage of current into undesired paths, such as occur in most of the types of granular carbon resistor furnaces, or types of furnaces in which refractory resistors have heretofore 75 been used, may thus be avoided.
- In some types of resistors, the resistor elements are liable to shrink to a greater or less degree in practice, thus impairing the continuity of the circuit. This is particularly 80 the case where the resistor is of a type used for carrying out chemical reactions, in which the resistor elements consists of blocks constituting the charge, as in the case of those above described for the production of aluminum nitrid, for example. My invention accordingly also contemplates the provision or means for maintaining the continuity of the electric circuit. I may use any suitable means for this purpose. As one convenient 85 form of means, see Fig. 2, I may provide a piston secured to the tube 8 by any suitable means as by soldering for example, said piston 36 being adapted to travel in a cylinder 38. The cylinder is mounted upon a suitable support, herein a casting 39 which may be water cooled and from which the cylinder head 40 is preferably insulated by a layer 42 of any suitable insulating material. To the casting 39 is secured a slab of any suitable 90 electrically conductive material, herein a graphite slab 44, by screw studs 46, 46 of any suitable electrical material, said studs being herein preferably made of graphite. Between the graphite slab 44 and the casting 95 39, I preferably place a layer 48 of any suitable refractory material to minimize the escape of heat from said graphite slab to said casting.
- The tube 8 is insulated from the water 100 cooled casting by an air space 50 and preferably also by an insulating bushing 52.
- One terminal of an electric circuit is electrically connected in any suitable manner 105 not shown to an electric conductor 54, herein 110 securely clamped between the flanges of the cylinder and cylinder head, while the other terminal of said circuit is connected to the water cooled casting. The current from one terminal thus passes from the cylinder into 115 the piston, thence into the water cooled conductor 8, and water cooled casting 10 and thence into the carbon block 4 and from the latter through the series of resistor elements 120 into the graphite slab 44. From the latter, 125

the current passes through the graphite studs 46, 46 to the water cooled casting 39 and thus to the other terminal of the circuit. A thin layer of mercury 56 will preferably be provided within the cylinder 38 to perfect the electric contact between the piston 36 and said cylinder.

Air, or any other suitable medium, from any suitable source of supply under pressure, 10 not shown, is admitted into the cylinder between the piston and the cylinder head 40 through a pipe 58, the admission being controlled by any suitable means such as a valve 60 provided in said pipe. As the blocks 15 shrink during the progress of the nitrification or other chemical process, the air pressure thus acting upon the piston within the cylinder will exert sufficient stress upon the tube or conductor 8 to maintain all the resistor elements of the resistor unit in firm 20 electrical contact with each other and with the carbon blocks 4 and 6 and the latter in firm contact with the graphite slab 44. The electric circuit will thus be kept complete at all times in spite of any shrinkage 25 that may occur in the resistor.

When the above described shrinkage takes place it does not always take place uniformly, so there may be a tendency of the resistor to warp out of a straight line. The resistor is kept from collapsing in such case by reason of the fact that such warping is arrested as soon as the resistor elements come in contact with the graphite sleeves 26. The 30 latter are electrically sectionalized by the insulating blocks 28 for the purpose of preventing current from passing endwise through said graphite sleeves, in case such accidental contacts should occur.

40 It will be apparent to those skilled in the art that resistors embodying my invention possess many advantages over resistors heretofore used. Thus, a resistor embodying my invention may be placed and will function 45 in any position best suited for the purpose for which it is used. For example it may be entirely suspended from above so as to hang naturally in a vertical position below the point of support. Where a plurality of 50 the units are used, each one may thus be suspended out of contact with the others so that each one will be completely insulated electrically from each of the others. They may thus be suspended out of contact with 55 the walls of the apparatus in which they are used. This is peculiarly advantageous where the resistor elements consist of blocks for carrying out chemical reactions, and more particularly for carrying out chemical 60 reactions between solid and gaseous bodies, as free access will thus be given the gas to all sides of the block. On account of the fact that each unit may thus be isolated, it is possible and even desirable to supply each 65 unit with current from an independent

source, so that the amount of energy delivered to each unit is independent of the amount delivered to any other. The electric circuit is maintained at all times in spite of any possible shrinkage or displacement of 70 the resistor elements by reason of the chemical reaction occurring therein or for any other reason and collapsing of the column due to possible warping or any other cause is also prevented as already fully explained. 75

It will also be noted that connection with the two terminals of the circuit supplying current to the resistor may be made at substantially the same point, adjacent one end of the resistor for example. When the resistor is suspended or otherwise disposed with one end at or near the upper or open end of a furnace or other apparatus, connection with both terminals of the supply circuit may thus be made at said upper or 80 said open end, thus greatly facilitating the making of said connections.

Other advantages secured by my invention, in addition to those herein specifically pointed out, will appear to those skilled in 90 the art.

It will be understood that, while the invention is herein described as embodied in the details illustrated, the invention is not to be considered as circumscribed by or 95 limited to these details or any of them, but that said details may be variously modified within the true scope of the invention which is definitely set forth by the claims. It will be understood also that it is not indispensable 100 that all the features of the invention be used conjointly, since they may be used to advantage separately in various combinations and sub-combinations, as defined in the subjoined claims. 105

Claims

1. In combination, an electrical resistor; an electrical conductor electrically connected to one end of said resistor and extending substantially axially thereof but not electrically connected to the other end of said resistor; means for connecting said conductor to one terminal of an electric circuit; and means for connecting the other end of said resistor to the other terminal of said circuit. 110

2. In combination, an electrical resistor; an electrical conductor electrically connected to one end of said resistor; fluid cooling means for said conductor effective coextensively with the resistor; means for connecting said conductor to one terminal of an electric circuit; and means for connecting the other end of said resistor to the other terminal of said circuit. 115 120

3. In combination, an electrical resistor; an electrical conductor extending substantially axially of the resistor and electrically connected to one end of said resistor; heat insulating means for said conductor exterior 130

to the latter; conductor cooling means within said conductor; means for connecting said conductor to one terminal of an electric circuit; and means for connecting the other end 5 of said resistor to the other terminal of said circuit.

4. In combination, an electrical resistor; an electrical conductor; and means operative throughout said resistor to prevent 10 overheating of said conductor.

5. In combination, an electrical resistor comprising a plurality of resistor elements forming part of an electric circuit; and means to maintain the continuity of said 15 electric circuit through said resistor elements.

6. In combination, an electrical resistor comprised of an electric circuit; and means to maintain the continuity of the circuit 20 through said resistor.

7. In combination, an electrical resistor; an electrical conductor electrically connected to one end of said resistor; means for connecting said conductor to one terminal of 25 an electric circuit; means for connecting the other end of the resistor to the other terminal of said circuit; and means to preserve the continuity of said electric circuit through said resistor.

8. In combination, an electrical resistor; means abutting against one end of said resistor; means abutting against the other end of said resistor; an electrical conductor connected to one of said abutting means but 35 disconnected from the other; and means to exert stress upon said conductor to maintain electrical contact between said resistor and said abutting means.

9. In combination, an electrical resistor 40 comprising a plurality of resistor elements; means abutting against one end of said resistor; means abutting against the other end of said resistor; an electrical conductor connected to one of said abutting means but disconnected from the other; and means to exert stress upon said conductor to maintain 45 electrical contact between said resistor elements and between said resistor and said abutting means.

10. In combination, an electrical resistor; an electrical conductor electrically connected to one end of the latter; means electrically connecting the other end of said resistor to one terminal of an electric circuit; and means electrically connecting said conductor to the other terminal of said circuit; and means to suspend said resistor by said conductor.

11. In combination, an electrical resistor 60 comprising one or more resistor blocks containing materials for carrying out a chemical reaction; an electrical conductor extending lengthwise of said resistor and electrically connected at one end to one end of said resistor; means for connecting the other end

of said conductor to one terminal of an electric circuit; and means for connecting the other end of said resistor to the other terminal of said circuit.

12. In combination, an electrical resistor 70 comprising one or more resistor blocks containing materials for carrying out a chemical reaction; an electrical conductor extending lengthwise of said resistor and electrically connected at one end to one end of said resistor; cooling means for said conductor; means for connecting the other end of said conductor to one terminal of an electric circuit; and means for connecting the other end of said resistor to the other terminal of said circuit.

13. In combination, an electrical resistor comprising one or more resistor blocks containing materials for carrying out a chemical reaction; an electrical conductor extending lengthwise of the resistor and electrically connected at one end to one end of said resistor; heat insulating means for said conductor; means for connecting the other end of said conductor to one terminal of an electric circuit; and means for connecting the other end of said resistor to the other terminal of said circuit.

14. In combination, an electrical resistor comprising one or more resistor blocks containing materials for carrying out a chemical reaction; an electrical conductor extending lengthwise of the resistor and electrically connected at one end to one end of said resistor; means for connecting the other end of said conductor to one terminal of an electric circuit; means for connecting the other end of said resistor to the other terminal of said circuit; and means to preserve the continuity of said circuit through said resistor.

15. In combination, a resistor comprising one or more porous resistor blocks provided with a gas passage and containing a mixture of an aluminous material, a reducing agent and a binder; means to admit gas 110 to said gas passage; an electrical conductor electrically connected to one end of said resistor; means for connecting said conductor to one terminal of an electric circuit; and means for connecting the other end of said resistor to the other terminal of said circuit.

16. In combination, a resistor comprising one or more porous resistor blocks provided with a gas passage and containing a mixture of an aluminous material, a reducing 120 agent and a binder; means to admit gas to said gas passage; an electrical conductor electrically connected to one end of said resistor; cooling means for said conductor; means for connecting said conductor to one terminal of an electric circuit; and means for connecting the other end of said resistor to the other terminal of said circuit.

17. In combination, a resistor comprising one or more porous resistor blocks provided 130

- with a gas passage and containing a mixture of an aluminous material, a reducing agent and a binder; means to admit gas to said gas passage; an electrical conductor 5 electrically connected to one end of said resistor; heat insulating means for said conductor; means for connecting said conductor to one terminal of an electric circuit; and means for connecting the other end of said 10 resistor to the other terminal of said circuit.
18. In combination, a resistor comprising one or more porous resistor blocks provided with a gas passage and containing a mixture of an aluminous material, a reducing 15 agent and a binder; means to admit gas to said gas passage; an electrical conductor electrically connected to one end of said resistor; means for connecting said conductor to one terminal of an electric circuit; means 20 for connecting the other end of said resistor to the other terminal of said circuit; and means to preserve the continuity of said circuit through said resistor.
19. In combination, an electrical resistor 25 adapted to be connected at one end to an electric circuit; and an electrical conductor electrically connected to the other end of said resistor and adapted to be connected to said electric circuit, adjacent the end of the 30 resistor that is connected to said circuit, said conductor being within said resistor.
20. In combination, an electrical resistor adapted to be connected at one end to one 35 terminal of an electric circuit; an electrical conductor within said resistor and electrically connected to the other end of the latter, said conductor being adapted to be connected to the other terminal of said electric circuit; and cooling means for said 40 conductor.
21. In combination, an electrical resistor adapted to be connected at one end to an electric circuit; an electrical conductor within said resistor and electrically connected to the other end of the latter, said conductor being adapted to be connected to 45 said electric circuit adjacent the end of the resistor that is connected to said circuit; and insulating means for said conductor.
22. In combination, an electrical resistor adapted to be connected at one end to an electric circuit; an electrical conductor within said resistor and electrically connected to the other end of the latter, said conductor being adapted to be connected to 50 said electric circuit adjacent the end of the resistor that is connected to said circuit; and means to preserve the continuity of said electric circuit through said resistor.
23. In combination, an electrical resistor; abutting means for one end of said resistor; abutting means for the other end of said resistor; an electrical conductor extending axially of said resistor and connected to one 55 of said abutting means but disconnected 60 from the other; and means to exert stress upon said conductor to maintain electrical contact between said resistor and said abutting means.
24. In combination, an electrical resistor; 70 abutting means for one end of said resistor; abutting means for the other end of said resistor; an electrical conductor extending axially of said resistor and connected to one of said abutting means but disconnected 75 from the other; and fluid operated means to exert stress upon said conductor for maintaining electrical contact between said resistor and said abutting means.
25. In combination, an electrical resistor 80 comprising a plurality of resistor elements placed end to end; abutting means for one end of said resistor; abutting means for the other end of said resistor; a conductor pipe extending axially of said resistor and connected to one of said abutting means but disconnected from the other; means to exert stress upon said conductor pipe to maintain electrical contact between the various elements of said resistor and said resistor and 85 said abutting means; and means for supplying a current of cooling fluid through said conductor pipe.
26. In combination, an electrical resistor comprising a plurality of resistor elements 90 placed end to end; abutting means for one end of said resistor; abutting means for the other end of said resistor; a conductor pipe extending axially of said resistor and connected to one of said abutting means but disconnected 95 from the other; a cylinder; a piston in said cylinder connected to said conductor pipe; and means for supplying a pressure medium to said cylinder at one side of the piston to exert stress upon said conductor pipe for the purpose of maintaining electrical contact between the several elements of said resistor and between the resistor and said abutting means.
27. In combination, an electrical resistor 100 comprising a plurality of resistor elements placed end to end; abutting means for one end of said resistor; abutting means for the other end of said resistor; a conductor pipe extending axially of said resistor and connected to one of said abutting means but disconnected 105 from the other; a cylinder; a piston in said cylinder connected to said conductor pipe; means for supplying a pressure medium to said cylinder at one side of the piston to exert stress upon said conductor pipe for the purpose of maintaining electrical contact between the several elements of said resistor and between the resistor and said abutting means; and means for supplying a current of cooling fluid through said conductor pipe.

In testimony whereof, I have signed my name to this specification.

WILLIAM HOOPES.
